US00D342054S

United States Patent [19] Woodman

[11] Patent Number: Des. 342,054

[45] Date of Patent: ** Dec. 7, 1993

[54] LIGHTED ELECTRICAL CONNECTOR

[75] Inventor: Bradley G. Woodman, Chicago, Ill.

[73] Assignee: Woodhead Industries, Inc.,
Northbrook, Ill.

[**] Term: 14 Years

[21] Appl. No.: 746,510

[22] Filed: Aug. 16, 1991

Related U.S. Application Data

[63] Continuation-in-part of Ser. No. 589,909, Sep. 28, 1990,
abandoned.

[52] U.S. Cl. 13/146

[58] Field of Search D13/133, 156; 439/426,
439/488, 489, 490

[57] CLAIM

The ornamental design for a lighted electrical connector, as shown and described in the drawings.

DESCRIPTION

FIG. 1 is a rear and upper right perspective view of a lighted electrical connector showing my new design; FIG. 2 is a plan view of the electrical connector of FIG. 1;

FIG. 3 is a rear elevation view of the electrical connector of FIG. 1;

FIG. 4 is a front elevation view of the electrical connector of FIG. 1;

FIG. 5 is a right side view of the electrical connector of FIG. 1, the left side view being a mirror image of the right side view;

FIG. 6 is a bottom view of the electrical connector of FIG. 1;

FIG. 7 is a rear and upper right perspective view of a lighted electrical connector showing a second embodiment of the design;

FIG. 8 is a plan view of the electric connector of FIG. 7;

FIG. 9 is a front elevation view of the electrical connector of FIG. 7, the rear elevation view being identical to FIG. 3 except for the coupling nut;

FIG. 10 is a right side view of the electrical connector of FIG. 7, the left side view being a mirror image of the right side view;

FIG. 11 is a bottom view of the electrical connector of FIG. 1;

FIG. 12 is a front and upper left perspective view of the electrical connector of FIG. 7; and,

FIG. 13 is a front and upper left perspective view of the first embodiment.

FIG. 2**FIG. 1****FIG. 3****FIG. 4****FIG. 5****FIG. 6**FIG. 6a

FIG. 12

*FIG. 7**FIG. 8**FIG. 9**FIG. 10**FIG. 11*
